Attorney.

UNITED STATES PATENT OFFICE.

JOHN L. HYLAND, OF ST. PAUL, MINNESOTA.

BOAT-LAUNCHING APPARATUS.

1,304,316.

Specification of Letters Patent.

Patented May 20, 1919.

Application filed September 17, 1917. Serial No. 191,853.

To all whom it may concern:

Be it known that I, JOHN L. HYLAND, a citizen of the United States, residing at St. Paul, in the county of Ramsey and State of Minnesota, have invented certain new and useful Improvements in Boat-Launching Apparatus, of which the following is a specification.

My invention relates to improvements in launching apparatus designed particularly for use in connection with ship's life boats, such as are particularly adapted for launching from davits.

The invention consists essentially of an apparatus in the form of a skid attachment which is adapted to be fitted to any ship's life boats amid-ships, but not to be in any way attached thereto, and arranged so that as soon as the boat is safely launched and clear of the ship the apparatus may be quickly freed from the boat.

The apparatus is so constructed as to hold the life boat in an upright position and guard it from being broken or damaged by contact with the ship's side, and prevent the life boat from dropping into openings between the decks or catching on the ship's side, etc.

My invention consists in the features of construction in combination hereinafter particularly described and claimed.

In the accompanying drawings which are a part of this specification,

Figure 1 is a sectional view through a life boat showing one form of my apparatus arranged in connection therewith,

Fig. 2 is a detail view illustrating a modification of my invention,

Fig. 3 is a similar view to Fig. 1, illustrating another modified form of my invention utilizing a double skid feature,

Fig. 4 is a detailed view of one form of my invention removed from the boat,

Fig. 5 is a sectional view of a portion of the invention illustrating a supporting caster, and

Fig. 6 is a partial detail of one of the skid members illustrating a lubricating device forming part of my invention.

Referring to the drawings, A designates an ordinary construction of life boat, which is adapted to be supported within the skid attachment as shown best in Figs. 1 and 3.

In the form shown in Fig. 1, my attachment as shown consists of two skid members

2 made of wood or of other material bent or shaped, as shown, to conform to the curvature of the boat, supporting blocks 3 at the bottom of the boat, being preferably secured upon the skid members.

4 represents cross-bars or blocks secured in separated position across the lower ends of the skid members 2, the keel of the boat, as shown, fitting between said blocks. The internal surfaces of the skid members and supporting blocks 3 are preferably covered with suitable yielding material 5 to engage with and prevent injury to the sides of the boat. To the lower ends of the skid members 2 are attached cables or chains 6, preferably through the medium of plates 7, secured to the lower ends of the skid members and curved to conform to the bottom of the boat. The cables or chains 6, as shown, terminate in a ring 8 to which a cable or chain 9 is attached. The other end of the chain or cable 9 is connected with a lever 10 adapted to removably pass through a bracket 11 connected to one end of each of the chains or cables 12, the other ends of the chains or cables 12 being connected to the upper ends of skid members as through the medium of a cross-bar 13. With the boat in position upon the skid members, as shown in Fig. 1, the cable or chain 9 will pass up over the side of boat 70 and across the top thereof with the lever 10 extending through the bracket 11 and secured as by means of a ring 14 loosely carried by the chain or cable 9 so as to be slipped over the end of the lever and hold the same 75 in position as shown in Fig. 1.

In the form illustrated in Fig. 1 the skid members are shown terminating just above the point of attachment of the cables 12. I may however, as shown in Fig. 4, provide the skid members with extensions 15 projecting above the gunwale of the boat, and where I do this, I preferably provide strut rods 16 connecting the bracket 11 with said extensions. Casters 17 may also be attached to the under-sides of the transverse members 4 for the purpose of allowing the boat to be freely moved upon the ship's deck.

In the modification shown in Fig. 2, the skid members terminate short of the keel of 105 the boat with plates 18 corresponding to the plates 7 secured to the lower ends of the skid members.

In this form I secure a cross-bar or block 110 upon the lower ends of the skid members,

and a block 20 upon the plates 18, the cross members or blocks 19 and 20 corresponding to the members 4 in the preferred construction.

- 5 In Fig. 3, I show skid members extending entirely around the bottom and sides of the boat so as to allow the boat to be launched from either side. In this modification, I simply extend skid members corresponding
10 to skid members 2 entirely around the bottom and sides of the boat and provide duplicate supporting blocks 3. I also employ blocks 21 secured upon the curved bottoms of the skid members to form a support for
15 the cross members or blocks 4.

I also show in Fig. 3 the upper ends of the strut members fastened over the edges of or inside the boat, whereby to allow boats to be packed one within the other.

- 20 In launching a life boat in the ordinary manner by the use of davits, particularly where the ship is sinking and has taken a list, great difficulty is experienced in keeping the boat out of contact with the side of
25 the ship and preventing it being damaged, etc., and also in preventing the boat passing between the decks or otherwise being caught. With the use of my improved skid apparatus as shown, these difficulties are obviated
30 and the boat can be safely launched without damage or difficulty under all conditions.

In Fig. 6, I show the skid member formed with an exterior groove 22, a tongue 23 being secured at one end so that it is free and
35 will stand over said groove. Thus in use of the apparatus, as the tongue 23 comes in contact with a solid part, as the ship, it will be forced thereby into the groove, forcing out lubricant that may be placed in the groove
40 to lubricate the exterior of the skid members.

For the purpose of lubricating the outer surface of the skid members, suitable means, such as shown in Fig. 6 may be employed.

- 45 My improved skid apparatus further acts as a protection to the boat to prevent its breaking up in launching.

I do not restrict myself to the exact construction shown, but may modify the details
50 of construction without departing from my

invention, the scope of which is defined in the following claims.

I claim:

1. A boat launching apparatus comprising a removable skid constructed to receive 55 a boat and fastening means removably supporting a boat within said skid.

2. A boat launching apparatus comprising a skid interiorly fitted to the contour of the boat and means carried by said skid and 60 extending across the top of a supported boat to removably secure the same upon said skid.

3. A boat launching apparatus comprising a skid interiorly conforming to the curvature of the boat, cable connections attached 65 to said skid and extending over a supported boat and means securing said chain or cable in position holding a supporting boat upon said skid.

4. A boat launching apparatus comprising 70 a skid constructed to removably support a boat and means carried by said skid and surrounding said boat removably securing a supported boat upon said skid.

5. A boat launching apparatus comprising 75 a skid constructed to receive a boat, and fastening means carried by said skid and extending over a supported boat for the purpose set forth.

6. A boat launching apparatus comprising 80 a skid constructed to receive a boat, means carried by the bottom of said skid forming an intermediate space to receive the boat keel and fastening means carried by said skid and extending over said boat for 85 the purpose set forth.

7. A boat launching apparatus comprising 90 a skid constructed to receive a boat, a yielding lining for said skid, a cable carried by said skid and extending over a supported boat and means for securing said cable in position holding a boat supported upon said skid.

In testimony whereof I affix my signature in presence of two witnesses.

JOHN L. HYLAND.
